UNITED STATES PATENT OFFICE.

HENRY TSCHERNING, OF FREEPORT, ILLINOIS, ASSIGNOR TO ARCADE MANUFACTURING COMPANY, OF FREEPORT, ILLINOIS, A CORPORATION OF ILLINOIS.

SPRING-HINGE.

SPECIFICATION forming part of Letters Patent No. 747,274, dated December 15, 1903.

Application filed August 1, 1903. Serial No. 167,835. (No model.)

To all whom it may concern:

Be it known that I, HENRY TSCHERNING, a citizen of the United States of America, residing at Freeport, in the county of Stephenson 5 and State of Illinois, have invented certain new and useful Improvements in Spring-Hinges, of which the following is a specification.

My invention relates to certain improvements in spring-hinges of the class known as "holdback" spring-hinges, which are intended for use upon screen-doors and the like and which are preferably so constructed as to exert the tension of the spring to hold the door 10 either closed or wide open and to return the door to either of these positions when slightly removed therefrom. When thus constructed, these hinges are arranged to close the door from any position into which it may be brought 15 in ordinary use in passing through it and to throw the door wide open and hold it in that position if open beyond the limit in ordinary use. The extensive use to which hinges of this class have been applied and the sharp 20 competition in their manufacture has made it exceedingly desirable that the hinges be made as cheap and simple as possible, that the greatest attention be given to the spring provided therein, so that it may not be of 25 such a nature or so applied to the hinge as to be likely to become set or lose its tension, and that the hinge as a whole be easy of attachment to the door-casing, so that both 30 door and hinge may be readily removed therefrom at the end of the season during which 35 the screen-doors are needed.

To these ends and others my invention consists in certain features of novelty which will appear in the following description and the 40 essential characteristics of which will be pointed out in the claims.

In the drawings, Figure 1 is a face view of the hinge, showing the same applied to the casing and door and showing the latter in its 45 closed position. Fig. 2 is a horizontal section looking downward in line 2 2 of Fig. 1. Fig. 3 is a vertical section looking in the direction of the arrow in line 3 3 of Fig. 1. Fig. 4 is a 50 view similar to Fig. 1 of the right-hand leaf of the hinge, and Fig. 5 is a similar view of

a fastening-plate by means of which the right-hand leaf is secured to the casing.

Referring to the drawings, A B are the two leaves of the hinge, which are preferably of sheet metal, turned at right angles at their 55 opposite ends to form the ears or knuckles a a' b b', which are pivoted together by means of rivets C C'. The inner edge of the leaf B is rolled backward to form a longitudinal socket b², and adjacent to the upper end thereof, as shown in the drawings, a tongue b³ extends past the pivotal axis of the spring into a notch a² in the leaf A. The socket and tongue provide means for securely holding in 60 position a U-shaped spring D, having a coil 65 d at its middle portion to increase its limit of elasticity and a transverse bend d' to rest against the tongue b³ and prevent the spring from pivoting upon one of its arms which is held in the socket d². The leaf A has a tongue 70 a³ extending therefrom past the pivotal axis of the hinge and perforated at a⁴. This tongue is connected to the other end d² of the spring by means of a link E, passing around the end 75 of the spring and through the perforation in the tongue. The action of the spring upon the hinge will be understood from an examination of Fig. 2. The tension of the spring is of course such as to tend to separate the arms therefrom, so that when in the position seen in Fig. 2 80 the spring tends to draw the plate A toward the plate B behind the pivotal axis of the hinge, therefore tending to draw the door toward the closed position. Said door is lettered X and the door-casing Y. If now the 85 door be brought forward from the position seen in Figs. 1 and 2, the link E, which connects the spring with the tongue a³ of the leaf A, will swing upon its pivotal connection until said link passes through the hinge-axis, 90 and thereafter the spring will tend to draw the two leaves of the hinge together upon the opposite side of the pivot, thereby tending to hold the door open.

It is intended that this hinge shall be secured to the door by means of screws in the ordinary manner. It is to be attached to the casing, however, by means of a fastening-plate F. (Shown separately in Fig. 5 by means of a face view.) Said plate consists of two 95 100

flat portions $f f'$, which are to be screwed to the door-casing and which are connected by a central bridge f^2 , which is bent forward into the form of a staple or socket. The leaf 5 A has a perforation a^5 , fitted to this socket and formed by bending the metal of the leaf, which is displaced therefrom back upon itself to form forwardly-convex portions $a^6 a^7$. When the leaf is placed upon the fastening- 10 plate with the socket extending through this perforation, a nail or pin G is passed through the socket and is preferably of such size as to put under tension both the metal of the socket and of the convex portions $a^6 a^7$ of the leaf A. Such tension serves to hold the pin 15 in place and also to secure the leaf A in position.

I claim as new and desire to secure by Letters Patent—

20 1. In a spring-hinge, the combination of two leaves pivoted together, one of which is formed with a longitudinally - extending socket adjacent to the meeting edges of the leaves, the other leaf being formed with a 25 tongue projecting laterally over and above the first-named leaf, a U-shaped spring supported wholly upon the first-named leaf, one of the legs of which is seated in said socket and bent at the end to engage the leaf to prevent 30 bodily rotation of the spring in said socket, and a link connecting the free end of the spring with the tongue upon the other leaf.

2. The combination with the pivoted leaves 35 of a hinge, one of which is provided with a perforation and wedge portions adjacent

thereto, of a fastening-plate having a socket fitted to said perforation and adapted to extend therethrough, and a pin fitted to said socket and adapted to wedge itself between 40 the same and the leaf of the hinge.

3. The combination with the pivoted leaves of a hinge, one of which is provided with a perforation and elastic portions adjacent thereto, of a fastening-plate having a socket 45 fitted to said perforation, and a pin adapted to enter said socket and bear closely upon said spring portions.

4. The combination with the pivoted leaves of a hinge, one of which is provided with a 50 suitable perforation, of a fastening-plate composed of two flat portions, f, f' , connected by a forwardly-projecting bridge or socket portion, f^2 , fitted to said perforation.

5. The combination with the pivoted leaves 55 of a hinge, the metal of one leaf of which is displaced to form a perforation, the displaced metal being folded back upon the leaf to form elastic portions adjacent to the perforation, of a fastening-plate having a socket adapted 60 to register with the perforation, and a pin adapted to enter the socket and bear upon the spring portions to hold the fastening-plate and leaf closely together.

In witness whereof I have signed the above 65 application for Letters Patent, at Freeport, in the county of Stephenson and State of Illinois, this 24th day of July, A. D. 1903.

HENRY TSCHERNING.
